MOUNTING ASSEMBLY FOR FLUORESCENT FIXTURES

Andrew O. Locke, Denver, Colo.

Application September 13, 1947, Serial No. 773,744

4 Claims. (Cl. 240—51.11)

1

This invention relates to new and useful improvements in mounting assemblies for fluorescent fixtures.

The invention relates particularly to an improved mounting means which facilitates installation of a fluorescent fixture. The usual fluorescent lighting fixture has considerable weight and because of its relative length is more or less bulky and difficult to handle. The required electrical connection between the fixture and the electrical supply wires must necessarily be made prior to the fastening of the fixture in its final mounted position on the ceiling or other overhead support and the bulkiness, as well as the relatively heavy weight, of the fixture present quite a problem in making the installation. Furthermore, substantially all of the fixtures now in general use require that the fixture be dismantled, either partially or completely, in order to permit its installation.

It is one object of the present invention to provide an improved fluorescent lighting fixture having means for supporting the complete fixture in a position which will permit the necessary electrical connections to be made, after which the fixture may be moved to and fastened in its final mounted position on a ceiling or other overhead support, whereby installation of said fixture is facilitated and may be rapidly accomplished without the necessity of dismantling the fixture or removing parts thereof which must be later re-attached to the fixture after the electrical connections are made.

An important object of the invention is to provide an improved lighting fixture wherein a supporting element or hook, which depends from the ceiling or other surface to which the fixture is to be fastened, is adapted to be engaged by the fixture and functions to support the complete unit in a suspended position to allow the necessary electrical connections to be made; said supporting element being so constructed that when the fixture is moved into its final mounted position, said element continues to co-act with the fixture to assist in supporting said fixture in such final mounted position.

A particular object of the invention is to provide a fixture, of the character described, wherein a relatively light hanger member, which may be easily handled, is adapted to be secured to the ceiling or other support upon which the fixture proper is to be finally mounted, together with co-acting means on the hanger member and the fixture proper for suspending said fixture in a position with its electrical connections

2

readily accessible to permit said fixture to be electrically connected to the usual electrical supply wires, said co-acting means also functioning to support the fixture in its final position, with additional means on the hanger and fixture for firmly fastening the fixture in said final position.

Still another object of the invention is to provide an improved mounting for fluorescent fixtures wherein the fixture proper need not be detached or removed from the supporting hanger member after the electrical connections are made, the construction being such that without detachment or removal, the completely assembled fixture unit may be readily moved from its suspended position into its final mounted position on the ceiling or other overhead support.

A further object of the invention is to provide an improved mounting assembly for a fluorescent lighting fixture which is so arranged that the entire fixture may be suspended therefrom whereby dismantling or partial disassembly of the fixture is not required in order to permit the necessary electrical connections to be made.

The construction designed to carry out the invention will be hereinafter described together with other features of the invention.

The invention will be more readily understood from a reading of the following specification and by reference to the accompanying drawing, wherein an example of the invention is shown, and wherein:

Figure 1 is an isometric view of an improved fluorescent lighting fixture and mounting, constructed in accordance with the invention and illustrating the fixture in a suspended position which makes the electrical connecting wires readily accessible,

Figure 2 is a similar view showing the fixture in its final mounted position,

Figure 3 is a view, partly in section and partly in elevation, with parts broken away to clearly show the hanger member and hooks,

Figure 4 is an enlarged, transverse, sectional view taken on the line 3—3 of Figure 1, and with the fixture in a suspended position,

Figure 5 is a similar view with the fixture secured to the hanger member in its final position,

Figure 6 is an enlarged, isometric view of the screw and key slot connection between the hanger member and fixture,

Figure 7 is an isometric view of a modified form of hook which may be substituted for the supporting hooks shown in Figures 1 to 5, and

Figure 8 is a sectional view, showing still another modification of the invention.

In the drawings, the letter A designates a fluorescent lighting fixture which is constructed in the usual manner and which includes a body portion or shell 10, the curved lower portion of which forms the reflecting surface. As is usual practice, the body or shell is generally semi-circular in shape in cross-section and a plurality of radially extending lamp sockets 11 are suitably secured to the ends of the body and project outwardly therefrom, whereby elongate tubular lamps 12 may be supported on the fixture. The lamps are, of course, disposed adjacent to the reflecting surface and end caps 13 which are fastened to the ends of the body in any desired manner cover said ends and enclose the sockets 11 to improve the appearance of the fixture.

The transformers, starters and other mechanism (not shown) are mounted within the body or shell 10 in a usual manner and are not shown in detail herein. The usual electrical connecting wires B for making electrical connection with the fixture extend outwardly through the flat top back plate 10a of said fixture. The particular details of construction of the fixture A form no part of the present invention and any standard type of fluorescent lighting fixture is adaptable to the improved mounting assembly which forms the present invention.

In carrying out the present invention, a pair of longitudinal channel bars 14 and 15 are welded or otherwise secured to the upper surface or back plate of the fixture A and extend longitudinally along each side thereof. It is not necessary that the bars 14 and 15 be channel shaped, although it has been found that this particular shape imparts rigidity and strength to the fixture and is preferable for that reason. The upright leg 14a of the channel 14 is formed with a pair of spaced slots or openings 16 and the lateral or horizontal leg 14b of said bar is also formed with slots or openings 16a which form a continuation of the openings 16 in the upright or vertical leg, as is clearly shown in Figures 4 and 5. Immediately below each slot or opening 16a, the upper wall 10a of the body or shell 10 is provided with an opening 17 which is in registration with the slot. The upright or vertical leg 15a of the opposite channel 15 is formed with spaced key slots 18, the purpose of which will be hereinafter set forth.

For mounting the fixture on a ceiling or other supporting surface, a hanger or supporting plate 19 is provided and said hanger plate is formed with depending longitudinal flanges 20 and 21 on each side thereof. A central opening 22 is formed in the plate 19 and is arranged to receive the usual supporting stud 23 which is mounted centrally of the ordinary electrical outlet box 24. The electrical box 24, as is well known, is suitably mounted within the ceiling or other supporting surface 25 and the supporting stud 23 which extends through the opening 22 in the hanger plate 19 receives a nut 26, whereby the hanger plate is mounted in position against the ceiling or other supporting surface 25 (Figure 3). In such position the flanges 20 and 21 of the hanger plate depend downwardly. The electrical supply wires C which extend into the electrical box 24 may pass downwardly through an opening 27 formed in the plate adjacent to the opening 22. The plate may be formed with additional small openings 28 which make it possible to fasten the hanger plate to the ceiling or supporting surface by means of suspension screws in the event that the electrical box with the supporting stud 23 is not available.

A pair of hooks 30 have their upper ends

secured to the depending flange 20 and as is clearly shown in Figures 1 and 3, the hooks are spaced from each other, being located adjacent opposite ends of the flange 20. Each hook has the upper end of its shank disposed horizontally as indicated at 30a and is then bent downwardly so as to extend in a vertical plane as indicated at 30b. The lower end of the vertical shank portion is curved upwardly to form the hook 30c.

As has been pointed out, the mounting and assembly of a fluorescent light fixture present certain difficulties because the assembled fixture A is relatively heavy and has considerable length, thereby making it bulky to handle. It is, of course, necessary that the electrical connecting wires B of the fixture be connected with the supply wires C and while this connection is being made, the fixture must be supported in some manner adjacent the location of the supply wires. With the fixture herein described, the hanger plate 19, which is relatively light in weight is first mounted on the ceiling or other supporting surface 25 either by the stud 23 as illustrated or by suitable screws which may extend through the openings 28. The electrical supply wires C are threaded downwardly through the opening 27 and have their ends clearly exposed below the plate.

The fixture A is then lifted into position so as to engage the hooks 30c of the hook members 30 with the sockets or openings 16 in the longitudinal channel member 14. Because the channel member is disposed at one longitudinal edge of the fixture A, the fixture will be supported in an inclined position as shown in Figure 4. In such position, the upper surface of said fixture is readily accessible and the fixture wires B are clearly exposed, whereby said wires may be easily connected with the electrical supply wires C. It is noted that at this time, the entire weight of the fixture is supported by the hook members 30 and the electrician or other person installing the fixture need not be concerned with supporting the weight of said fixture.

After the electrical connection is made, the fixture A is moved upwardly with the vertical leg of the channel being slid upwardly along the vertical shank portion 30b of each hook member. This upward movement of the fixtures causes the hook portion 30c of each hook member to enter the interior of the body or shell through the openings 16a and 17. Continued upward movement of the fixture causes the slot 16 in the upright leg 14a of the channel bar 14 to engage over the lateral or horizontal portion 30a of each hook member so that this side of the fixture is supported by the hook member. At this time, the hook portion 30c and the lower portion of the vertical shank 30b are disposed within the interior of the body or shell 10 of the fixture. To prevent this member from entangling with any of the internal equipment, U-shaped hook guards 31 are secured to the underside of the top back plate 10a of the shell and as the hooks move downwardly into the shell, they are disposed within the guard members 31.

After the fixture has been moved upwardly to suspend the channel bar 14 from the upper end of the hook members 30, the channel bar 15 is moved forwardly and upwardly so as to engage its key slots 18 over outwardly extending fastening screws 32. Each fastening screw 32 has its inner end threaded into a nut 33 which is welded or otherwise secured to the inner surface of the depending flange 21 of the hanger plate. Because of the key slots 18, the heads of the fas-

tening screws 32 may pass outwardly through the vertical leg 15a of the channel bar 15 and the reduced portion 18a of each key slot is engaged with the shank of each screw. The screws 32 may then be tightened to securely fasten the fixture A in position on the hanger plate 19.

It will be evident that in its finally mounted position, the fixture A has one side supported by the hook members 30 while its opposite longitudinal side is supported by the fastening screws 32. If for any reason it is necessary to examine the electrical connection between the wires B and C, the screws 32 may be loosened sufficiently to permit the fixture to be moved upwardly and then outwardly so as to disconnect the channel bar 15 from the hanger plate. When this is done, the fixture may be readily swung to its lower or suspended position, as shown in Figure 4 which clearly exposes the upper surface of said fixture and permits any desired work to be done on the electrical connection. It is noted that the hook members 30 may be of any desired length, although it is preferable that they be sufficiently long to provide for access to the upper surface of the fixture when said fixture is in its suspended position.

As has been stated, the longitudinal channel bars 14 and 15 are desirable since they have the additional feature of adding strength to the fixture. However, these bars could be only sufficiently long to accommodate the slots 16 which receive the hooks or individual lugs having the slots therein could be substituted therefor. Also, it is not essential that the hanger plate have the longitudinal flanges 20 and 21 since depending lugs having the hooks 30 attached thereto and the screws 32 mounted therein would serve the same purpose.

In Figures 1 to 6 two hook members spaced apart have been illustrated and in Figure 7 a modified form of a hook element is shown. In this modification a flat type hook member 35 is secured to the central portion of the flange 20 and the hanger plate 19. In place of the slots 16 and 16a in longitudinal channel bar 14, a relatively wide slot 37 in its vertical leg portion and a communicating slot 38 in its horizontal portion are provided, these slots functioning in the same manner as the slots or openings 16 and 16a in the channel bar 14. It will be evident that the hook member 35 and its co-acting connecting element 36 will operate in identically the same manner to support the fixture A in a suspended position and yet permit the same to be moved into a final mounted position on the hanger plate. In Figure 8 still another modification of the manner of connecting the hook members 30 to the fixture is illustrated. In this modification the top back plate 10a of the shell 10 is formed with slots 40 and 41, each pair of slots 40 and 41 being provided for each hook. As is clearly shown in Figure 8 the slot 40 has sufficient length to permit introduction of the hook portion 30c of its corresponding hook member into the interior of the shell and when said hook portion has entered the shell, its upper extremity may engage within the slot or opening 41 to mount the fixture in a suspended position with its electrical connecting wire clearly exposed and readily accessible. It will be obvious that the fixture may be moved to its finally mounted position in the same manner as hereinbefore described, with the underside of the top 10a adjacent the end of the slot 40 engaged with or resting upon the lateral portion 30a

of each hook member. With this modification, the use of the separate channel bar 14 such as shown in Figures 1 to 6, or a supporting lug as shown in Figure 7, is entirely eliminated.

From the foregoing it will be seen that a simple and efficient mounting assembly is provided. The arrangement is such that the fixture may be completely assembled prior to its connection with the electrical lead wires C and before it is raised upwardly for engagement with the hook members. Partial or complete dismantling of the fixture is not necessary in order to make the installation. The fixture is independently supported on the hook member 30 with its upper surface and its connecting wires exposed and readily accessible. After the necessary electrical connections are made, the complete fixture unit may be quickly and easily swung into a finally mounted position without having to re-attach any parts thereto and without disconnecting the fixture from the hooks which support it in its suspended position. The hooks are so arranged that they not only function to support the fixture in its suspended position but also co-act to assist in supporting the fixture after it has been moved to its finally mounted position. The assembly is extremely simple and facilitates the installation of fluorescent lighting fixtures.

The foregoing description of the invention is explanatory thereof and various changes in the size, shape and materials, as well as in the details of the illustrated construction may be made within the scope of the appended claims, without departing from the spirit of the invention.

What I claim and desire to secure by Letters Patent is:

1. A mounting assembly for a lighting fixture including, a hanger plate adapted to be attached to a supporting surface, a hook element secured to said plate at one side thereof and depending therefrom, said hook element including a vertical shank having a hook at its lower end and an offset horizontal supporting surface at its upper end, an elongate lighting fixture unit, an upwardly extending projection on said unit at one side thereof and having a slot therein, whereby the hook of said hook element may be engaged therewith to suspend the fixture from said plate with its electrical connections readily accessible, the slot in said projection being elongate to permit the fixture unit to be moved upwardly to a final position adjacent the hanger plate with the projection engaging the horizontal offset at the upper end of the hook element, and fastening means for securing the fixture unit to the hanger in said final position.

2. A mounting assembly for a lighting fixture including, a substantially flat hanger plate having longitudinal depending side flanges, a pair of depending hooks secured to one of said flanges, each hook having an offset supporting surface at the upper end of its shank fastening screws in the opposite side flange, a fluorescent lighting fixture unit, having an upstanding projection at one side of its upper surface, said projection having slots therein for receiving the hooks of the hanger plate, whereby the fixture unit may be supported in an inclined suspended position, an upstanding flange on the upper surface of the unit on the side opposite the projection and having key slots therein, said fixture being movable upwardly on the hooks into a final position adjacent the hanger plate with the upstanding projection engageable with the offsets in the hook shanks which support that side of the fix-

ture; such movement permitting engagement of the key slots in the flange of the fixture unit with the screws in the hanger plate, whereby the unit may be securely fastened to the hanger plate in its final position.

3. In combination, a fluorescent lighting fixture having an elongate generally rectangular body and a supporting member therefor, said supporting member comprising a substantially flat plate, a hook element secured to the plate at one side thereof, and depending therefrom, said hook element including a vertical shank portion having an offset horizontal supporting surface at its upper end and a hook section at its lower end, the body of the light fixture having an opening in its upper surface for receiving the hook element, an upright connecting member secured to the upper surface of the fixture body adjacent the opening in said body and extending upwardly from said surface, said connecting member having an opening therein engageable with the hook section of the hook element for suspending the fixture from said hook section, the connecting member being movable upwardly on the hook element and into engagement with the offset horizontal supporting surface of the hook element to support one side of the fixture body in a position adjacent the supporting plate, and means for attaching the opposite side of the fixture body to the supporting plate.

4. In combination, a lighting fixture having an elongate generally rectangular body and a supporting member therefor, said supporting member comprising a substantially flat plate having longitudinal depending side flanges, a pair of hook elements secured to one of the flanges in spaced relationship and depending therefrom, each hook having the major portion of its shank in a vertical plane with the upper end of the shank bent upon itself to form a horizontal offset

supporting surface, upright connecting elements on the upper surface of the body of the lighting fixture and spaced apart substantially the same distance as the side flanges of the supporting member whereby the connecting elements will abut said flanges when the fixture is moved upwardly against the plate, one of said elements having openings therein adapted to receive the hook elements to suspend the fixture from the lower ends of said hooks, said openings being movable upwardly on the hook shanks to engage the offset supporting surfaces of the hook shanks with the connecting element in which said openings are mounted, and means for attaching the second connecting element to the second flange of the plate when the first connecting element is supported by the offset portions of the hook shanks.
